READILY DISMEMBERABLE VALVE ASSEMBLY FOR SANITARY DISPENSATION OF FLUID

George A. Goepfrich, Norwalk, Conn., assignor to
The Skinner Chuck Company, New Britain,
Conn., a corporation of Connecticut

Application April 15, 1949, Serial No. 87,596

10 Claims. (Cl. 137—719)

1

Although susceptible of use in many applications requiring control of fluid flow, the present invention is particularly advantageous in applications wherein sanitation and ease of servicing large numbers of installations in widely separated locations are prime requirements, for example, in automatic coin operated vending machines for dispensing measured quantities of beverages for human consumption. In that connection, it will be appreciated that governmental agencies frequently require the meeting of high and severe performance standards with regard to sanitation as a result of which it is highly desirable that a valve for such application incorporate as many as possible of such features as the following, all of which individually and in combination enhance the degree of sanitation with which the fluid may be handled: First, the essential valve mechanisms in contact with the fluid ought to be so constructed that they may be readily dismembered and detached from the dispensing machine proper so that they may be removed for cleaning or even for replacement by a new or freshly cleaned valve mechanism. Secondly, these essential elements ought to be so constructed that there is ready and relatively open access for cleaning fluid and instruments to penetrate into all ducts or chambers with which the beverage might come into contact. To the same end, the essential valve mechanisms ought to be isolated as much as possible from the mechanisms for interrupting the fluid flow such as the plungers or like devices operating the valve head. Lastly, although related more to servicing convenience than to the sanitation features, it is desirable not only that such a valve be easily installed, serviced or replaced with another valve by relatively unskilled hands, but also that it provide simple and convenient means for adjusting the rate of flow so that any desired predetermined quantity of fluid may be dispensed, for example, where a measured quantity is desired to be dispensed in accordance with coin operation of the machine.

Accordingly, it is a principal object of the invention to provide a valve of the foregoing character simple in construction and operation and incorporating one or more of the foregoing desired features.

The features of the invention upon which patent protection is sought are set forth in the appended claims. The invention itself together with further objects and advantages thereof, may best be understood by reference to the following specification when taken in conjunction with the

10 accompanying drawing in which: the Fig. 1 represents a cross-sectional view of one embodiment of the invention; the Fig. 2 represents a plan view viewed toward the right-hand end of the Fig. 1; while the Fig. 3 represents a partial cross-section along the line 3—3 of the Fig. 1 and illustrating keying mechanisms permitting convenient dismemberment of the valve structure proper from its actuating electromagnetic coil structure.

15 Referring now to the Fig. 1, the fluid handling portions of the valve structure are incorporated in a demountable valve assembly 10 detachably affixed to an electromagnet assembly 11, which itself may be affixed to any suitable support, such as the bracket 12, on the machine in which used (not shown). Bracket 12 will support both the valve assembly 10 and assembly 11 when the latter is affixed to it. The two assemblies 10 and 11 may be readily dismembered and separated from each other (approximately along the line 3—3) by manual operation of key means to be described later in further detail. It will at once be apparent that the assembly 10 has the primary 20 merit that it may be readily removed for cleaning or replacement by an identical assembly which feature will understandably be of great convenience where a plurality of automatic dispensing machines in widely separated localities must be serviced periodically.

25 As to the detailed construction of the assembly 10, this may be built around the cylindrical metallic block 13 having an outlet channel 14 to which an outlet tube or spout 15 is detachably affixed, the inlet channel 16 to which the inlet tube 17 is detachably affixed, a valve seat 18 and a cooperating valve seat closing means such as a flexible rubber diaphragm 19, and a flow regulating meter 20. Fluid to be controlled may thus flow through the longitudinally and diametrically extending ducts respectively 17a and 17b of tube 17 into the inlet channel 16, thence through the duct 23 into the cylindrical valve chamber 22 between the diaphragm 19 and the body of the block 13, thence through the duct or port 21 communicating with the chamber 22 and the outlet channel 14 when the diaphragm 19 is away from the port or valve seat 18, so that fluids may be delivered through the outlet tube 15 by 30 pressure or by gravity as desired. If done by gravity, the whole assembly may be positioned such that tube 15 is on the downward side.

35 Channels 14 and 16 constitute opposite ends of a single cylindrical diametric bore in block 13 interrupted by axial cylindrical bore or orifice

55

25, as shown. Direct flow of fluid between the outlet channel 14 and the inlet channel 16 is prevented by the end of tube 17 and seal 32. Flow meter 20 comprises a cylindrical insert stem 24 closely fitting within a cylindrical receiving bore or orifice 25 and provided with the diagonal end surface 26. Rotation of the flow meter 20 by means of its cylindrical adjusting head 27 will cause the diagonal surface 26 to assume varying positions with respect to the port 21 and the channel 14 whereby to restrict controllably the cross-section of the portion 28 of orifice 25 interconnecting the channel 14 and the port 21. Thus in the position shown, because the diagonal surface slants downward, the maximum cross-section of the portion 28 is provided; rotation of the flow meter 20 through 180° will substantially close the cross-section of portion 28 to stop all fluid flow. In intervening positions between that shown and the 180° rotation of the flow meter, varying amounts of the flow between full flow and complete stoppage will be permitted at the will of the operator.

Tube 15, of metal or other suitable construction, is detachably yet rigidly affixed to the block 13, as by friction engagement, by means of the annular sealing ring 29 preferably of circular cross-section and preferably of resilient material such as rubber. The metallic washer 30 surrounding the tube 15 meshes with the inner periphery of the channel 14 as shown in order to retain ring 29 in position and to aid in the rigid positioning of the tube 15 with respect to block 13. With this construction, the tube 15, may be conveniently and readily inserted into the channel 14 by placement of the end thereof, with the rubber ring 29 attached, at the opening of the channel and manually pressing the assembly downward, in which case, rolling action of the rubber ring will facilitate the downward motion and at the same time provide a sealed connection between the block and the tube. Removal may be performed similarly.

The tube 17 is similarly constructed. At its narrowed inner end within the annular groove 31, it is provided with a similar annular sealing ring 32 substantially the same as the ring 29 above except for its decreased diameter. A second annular ring 33, like the rings 29 and 32 above, is likewise provided around the portion 34 of somewhat enlarged diameter of the spout 17. As with the tube 15 already discussed, the rings 32 and 33 on the outlet tubing or spout will likewise permit by their rolling action a convenient insertion or removal of the spout 17 into or from the outlet channel 16.

Because it is subject to inlet pressure tube 17 may be locked in its assembled position by means of the annular keying flange 35 thereon and the key member 36 affixed to the block. A suitable omitted arc-like portion of the flange 35 of sufficient size to permit rotary engagement or disengagement with the key member 36 is provided so that the spout may be removed by rotation to the point where the key member 36 and the omitted portion of the flange are in juxtaposition. Locking insertion may be accomplished in the reverse manner. The structure of the omitted portion is not shown but is essentially the same as that employed for the flow meter locking means presently to be described. It will be understood that, if desired, the tube 15 may be provided with like locking means.

The flow meter 20 may be similarly inserted into its receiving channel or orifice 25 by the aid of the

resilient annular ring 37 substantially the same as the rings 29, 32 and 33 and functioning similarly. In order to lock the flow meter within its channel, keying means in the form of the annular flange 38 on the head 27 and having a suitable omitted arc-like portion 39 cooperates with the key member 40 on the block 13 in a manner which is best indicated by the Fig. 2. It will there be apparent that the rotation of the head 27 will bring the flange omitted portion 39 to the point where it is free of engagement with the key member 40 so that the meter may be removed, or inserted and locked in the assembly. In assembled locked position, the flange 38 will rest under the key member 40 whereby the flow meter is locked in the assembly although it may still rotate for purposes of adjustment.

The valve chamber 22 is formed within the recess 41 of varying annular cross-sections in the end face of block 13. This structure includes an annular shelf 42 upon which the preferably circular rubber diaphragm 19 rests. The outer walls of the recess are provided with the key groove flanges 43 which, in effect, comprise sectoral portions of what would otherwise be a continuous peripheral flange except for interruption by or omission of sectors 44 around the periphery in a manner better indicated by the Fig. 3. This is for the purpose of permitting unlocking and locking with the keys 45 of key plate 46 likewise better illustrated by the Fig. 3. It will be apparent that if the key plate 46, which has the shape shown in Fig. 3, be inserted with its four corners (keys 45) in the sectors 44, then by turning of the key plate, the surfaces of keys 45 will engage the outwardly converging diagonal surfaces 47 of the key flanges 43 so that the whole structure is firmly locked together. Unlocking may be accomplished in the reverse manner. Between the key plate 46 and the diaphragm 19 there may be inserted a resilient means comprising a resilient wave or split ring washer 48 and an annular flat metallic washer 49 for the purpose of providing resilient yet rigid connection between the two assemblies 10 and 11.

The electromagnet assembly 11 is largely conventional by itself and consists essentially of the electromagnet coil 50 with its leads 51 and 52, and a movable magnetic core 53 biased normally toward the right by means of the spring 54 so that it will normally maintain the valve assembly in fluid flow blocking condition by pressure of the core 53 on the diaphragm 19 against the valve seat 18. Excessive motion of the core 53 which might cause it to come out of the assembly 11 when assembly 10 is disconnected therefrom, is prevented by means of the stud 55 having an end portion projecting into the annular recess 56 of the core. Recess 56 is wide enough to permit core 53 to contact fixed core portion 61. The core 53 is guided in its motion by the non-magnetic sleeve 57 (e.g., of brass or like material) concentrically mounted in the electromagnet structure. The rear and forward plates 58 and 59 together with the retaining housing 60 of the electromagnet are preferably of magnetic material in order to complete the magnetic circuits involved. The same is true of the fixed core portion 61. The electromagnet is preferably of the type operable by alternating current and to that end the usual conductive ring 62 is provided on the fixed core portion.

It will be understood that means (not shown) may be provided for energizing the electromagnetic coil for a predetermined interval of time so that a predetermined quantity of fluid may be

permitted to flow, for example, when the invention is employed in a coin operated beverage dispensing machine.

From the foregoing it will be apparent that the entire valve assembly 19 may be disassembled quickly and easily when it has been disconnected from the operator assembly 11 by the keying operation. Thereupon, because all the fluid flow channels within the assembly 19 are straight and readily accessible bores, they may be cleaned very easily. Moreover, the operator need not be concerned with the cleaning of the operating magnet assembly 11 since it has no contact with the fluid dispensed.

It will be understood that numerous modifications of the foregoing embodiment of the invention will occur to those skilled in the art. All such as fall within the true spirit and scope of my invention I aim to include within the appended claims.

What I claim is:

1. A dismemberable valve assembly adapted to be detachably affixed to a valve operator mechanism including an electromagnetic coil having a reciprocable plunger therein, and a key plate surrounding said plunger, for cooperation with said plunger, said assembly comprising a cylindrical block having a wall defining a cylindrical recess in one end face thereof, an annular shelf in said recess, a valve seat in the bottom of said recess within said shelf, a flexible diaphragm adapted to be held against said shelf by said key plate and constituting a closure member for said seat movable away from said seat by fluid pressure in the hereinafter mentioned first port and towards said seat by said plunger, said diaphragm defining with said shelf and the bottom of said recess a valve chamber, a diametric bore through said block and an axial bore in said block terminating in said valve seat, removable plug means in said axial bore separating said diametric bore into a first and a second port, said plug means and bores defining a first duct communicating with said first port and said valve seat, a second duct communicating with said second port and said chamber, said wall having key flanges adapted to cooperate with said key plate whereby, upon insertion of said key plate into said recess, said valve assembly and mechanism may be interlocked by mutual rotation and said diaphragm is held against said shelf by said key plate.

2. An assembly as in claim 1 in which said plug means comprises a cylindrical plug in said axial bore, said plug being rotatable and provided with means on its end toward said valve seat defining a portion of said first duct, said last-mentioned means being so constructed and arranged that the cross-section of said first duct is variable with rotation of said cylindrical plug.

3. A dismemberable valve assembly adapted to be detachably affixed to a valve operator mechanism including an electromagnetic coil having a reciprocable plunger therein, and a key plate, for cooperation with said plunger, said assembly comprising a cylindrical block having a wall defining a cylindrical recess in one end face thereof, an annular shelf in said recess, a valve seat in the bottom of said recess within said shelf, a flexible diaphragm adapted to be held against said shelf by said key plate and constituting a closure member for said seat movable away from said seat by fluid pressure in the hereinafter mentioned first port and towards said seat by said plunger, said diaphragm defining with said shelf and the bottom of said recess a valve chamber, a first port

in the cylindrical surface of said block communicating with said seat, a second port in said cylindrical surface of said block communicating with said chamber, said wall having key flanges adapted to cooperate with said key plate whereby, upon insertion of said key plate into said recess said valve assembly and mechanism may be interlocked by mutual rotation and said diaphragm is held against said shelf by said key plate.

4. A structure as in claim 3 including an adjustable flow regulator between said first port and said valve seat.

5. A dismemberable valve assembly adapted to be detachably affixed to a valve operator mechanism including an electromagnetic coil having a reciprocable plunger therein, and a key plate, for cooperation with said plunger, said assembly comprising a block having a wall defining a recess in one face thereof, a shelf in said recess, a valve seat in the bottom of said recess within said shelf, a flexible diaphragm adapted to be held against said shelf by said key plate and constituting a closure member for said seat movable away from said seat by fluid pressure in the hereinafter mentioned first port and towards said seat by said plunger, said diaphragm defining with said shelf and the bottom of said recess a valve chamber, a first port in another face of said block communicating with said seat, a second port in said another face of said block communicating with said chamber, said wall having key flanges adapted to cooperate with said key plate whereby, upon insertion of said key plate into said recess, said assembly mechanism may be interlocked by mutual rotation and said diaphragm is held against said shelf by said key plate.

6. A structure as in claim 5 including an adjustable flow regulator between said first port and said valve seat.

7. A valve assembly adapted to cooperate with a valve operator mechanism comprising a block having a wall defining a recess in one face thereof, a valve seat in said recess, a flexible diaphragm sealable across said recess and constituting a closure member for said seat operable by fluid pressure and said mechanism, said diaphragm defining with at least a part of said recess a valve chamber about said seat, a bore extending continuously through said block and having openings in different faces thereof, a second bore in said block and through said first bore terminating in said valve seat, removable plug means in said second bore separating said first bore into first and second ports, said bores and plug means defining a first duct communicating with one of said ports and said valve seat, and a second duct in said block communicating with the other of said ports and said chamber.

8. An assembly as in claim 7 in which said plug means in said second bore is adjustable in position and provided with means defining a portion of said first duct, said means being so constructed and arranged that the cross-section of said first duct is variable with movement of said plug.

9. A valve assembly adapted to be affixed to a valve operator mechanism including a reciprocable plunger therein, said assembly comprising a block having a wall defining a recess in one face thereof, a valve seat in the bottom of said recess, a flexible diaphragm sealable across said recess and constituting a closure member for said seat operable by fluid pressure and said plunger, said diaphragm defining with at least a part of said recess a valve chamber about said seat, a bore

extending continuously through said block and having openings in different faces thereof, a second bore in said block and through said first bore terminating in said valve seat, removable plug means in said second bore separating said first bore into first and second ports, said bores and plug means defining a first duct communicating with one of said ports and said valve seat, and a second duct in said block communicating with the other of said ports and said chamber.

10. An assembly as in claim 9 in which said plug means in said second bore is rotatable and provided with means defining a portion of said first duct, said means being so constructed and arranged that the cross-section of said first duct is variable with rotation of said plug.
